JAMES F. PERETI Inventor

By Watson E. Coleman

Attorney

UNITED STATES PATENT OFFICE.

JAMES FRANK PERETI, OF TRENTON, NEW JERSEY.

SIGNALING DEVICE.

1,217,628.

Specification of Letters Patent. Patented Feb. 27, 1917.

Application filed July 22, 1916. Serial No. 110,776.

To all whom it may concern:

Be it known that I, JAMES F. PERETI, a citizen of the United States, residing at Trenton, in the county of Mercer and State 5 of New Jersey, have invented certain new and useful Improvements in Signaling Devices, of which the following is a specification, reference being had to the accompanying drawings.

10 This invention relates to certain improvements in signaling devices and has relation more particularly to a device of this general character especially designed and adapted for use in connection with vehicles; and it 15 is an object of the invention to provide a device of this general character having novel and improved means whereby the direction of turn of a vehicle may be readily disclosed to a vehicle following.

20 It is also an object of the invention to provide a device of this general character including a signal with which an illuminating member is adapted to coact to facilitate its use after night-fall, together with means 25 whereby the operation of the illuminating member and the signal are under control of a single member.

The invention consists in the details of construction and in the combination and arrangement of the several parts of my improved signaling device whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the 40 better understood, I will now proceed to describe the same with reference to the accompanying drawings, wherein—

Figure 1 is a diagrammatic view partly in elevation and partly in section illustrating a 45 signaling device constructed in accordance with an embodiment of my invention;

Fig. 2 is a horizontal sectional view taken through the casing as herein disclosed;

Fig. 3 is a view partly in plan and partly 50 in section of the operating arm for the signal and its concomitant parts, a portion of the circuit for the illuminating member being diagrammatically illustrated; and

Fig. 4 is a fragmentary view illustrating 55 a modified form of my device.

As disclosed in Figs. 1 to 3, 1 denotes a

casing of predetermined dimensions and adapted to be suitably positioned upon the vehicle and provided with the visual opening 2 through which the indications on the 60 tape 3 are adapted to be exposed.

The casing 1 is provided with the vertically disposed shafts 4 arranged at opposite sides of the opening 2 and with which the tape 3 is engaged, and the lower end portions 65 of the shafts 4 within the casing 1 are provided with the gears 5 in mesh with the intermediate gear 6 fixed to the upper end of the vertically disposed shaft 7. It is thought to be self-evident that upon rotation of the 70 shaft 7 one of the indications will be swung in a position across the opening 2, while the second indication is swung into a position therefrom. In practice it is preferred that one of the indications be "Right" and the 75 second "Left" for purposes which are believed to be clearly apparent to those skilled in the art to which my invention appertains.

8 denotes a horizontal shaft disposed longitudinally of the vehicle with which the sign is employed and operatively engaged, as at 9, with the shaft 7 while the inner end of the shaft 8 is operatively engaged, as at 10, with the shaft 11 adapted to be supported by the steering column or the like of 85 an automobile.

Clamped, as at 12, to the steering column is a segment 14 provided with the hub portion 15. Fixed to the extended portion of the shaft 11 is the operating arm 16 which 90 underlies the segment 14 and is provided with the returned portion 17 overlying the same and is also provided with the spring-pressed pawl 18 adapted to coact with the teeth 19 arranged along the outer margin 95 of the segment 14.

The arm 16 is provided with a head 24 adapted to be operatively engaged with the upper extremity of the shaft 11 as is clearly shown in Fig. 1 and which is rotatably 100 mounted within the socket 25 produced in the under surface of the hub 15, as is also clearly shown in Fig. 1 of the accompanying drawings.

Arranged within the casing 1 and preferably at an end thereof is the lamp L preferably of an incandescent type and which is adapted to be suitably connected with a suitable source of energy through the conductor *a* with the shaft 11 which is of conductive material as is also the operating arm 16. The lamp L is also operatively con-

nected through the medium of the conductor *b* with the contacts 20 arranged in predetermined spaced relation upon the segment 14 and with which is adapted to coact the 5 elongated contact member 21 pivotally mounted intermediate its length upon the operating arm 16, whereby it will be perceived that when the contact member 21 is disposed transversely of the arm 16, an end 10 thereof may engage the top of either of the contacts 20, whereby a circuit will be closed and the lamp *L* illuminated. It is also to be noted that the segment 14 is provided with the shoulders 22 with which the 15 arm 16 is adapted to coact whereby the swinging movement of said arm is limited and it is to be further noted that said shoulders 22 are so positioned relative to the contacts 20 as to prevent the arm 16 proper 20 coming into engagement with said contacts.

It will be perceived that when the contact 21 is adjusted substantially longitudinally of the arm 16, the closing of the lamp circuit will not occur and which adjustment 25 of the contact 21 is preferred during the day. In order to facilitate the requisite adjustment of the contact 21 I find it of advantage to have the intermediate or pivoted portion thereof provided with the outstanding 30 button 23.

I have also found it desirable, as illustrated in Fig. 4, to have the plates 3^a under certain conditions to be secured directly to the shaft 7^a and in which instance said shaft 35 7^a is extended upwardly through the casing 1^a in order to permit the requisite adjustment thereto of the plates 3^a.

It is also to be noted that the clamping arms 26 are carried by the hub portion 15 40 of the segment 14 and through which a conventional headed member 27 is directed in order to properly apply the segment 14 in operative position.

From the foregoing description, it is 45 thought to be obvious that a signaling device constructed in accordance with my invention is of an extremely simple and comparatively inexpensive nature and is particularly well adapted for use by reason of 50 the convenience and facility with which it may be assembled, and it will also be obvious that my invention is susceptible of some change and modification without material departure from the principles and 55 spirit thereof and for this reason I do not

wish to be understood as limiting myself to the precise arrangement and formation of the several parts herein shown in carrying out my invention in practice, except as hereinafter claimed.

I claim:

1. A circuit closer comprising two relatively movable members, one of said members being provided with spaced contacts and the second member being interposed between said contacts, said members being provided with coacting means whereby the second member is prevented from engaging the contacts of the first member, and a contact member pivotally engaged with the 70 second named member and adapted to be extended beyond either side thereof for engagement with the contacts of the first named member.

2. A circuit closer comprising two relatively movable members, one of said members being provided with spaced contacts and the second member being interposed between said contacts, said members being provided with coacting means whereby the second member is prevented from engaging the contacts of the first member, a contact member pivotally engaged with the second named member and adapted to be extended beyond either side thereof for engagement with the 85 contacts of the first named member, and means for holding said members against relative movement when the contact member of the second named member is in engagement with one of the contacts of the first 90 named member.

3. A circuit closer comprising two relatively movable members, one of said members being provided with spaced contacts and a shoulder positioned inwardly of each 95 of said contacts, the second named member being provided with means adapted to contact with said shoulders to prevent said member from engaging the contacts, and a movable contact member carried by the second named member adapted to extend beyond either side thereof to engage a contact of the first named member.

In testimony whereof I hereunto affix my signature in the presence of two witnesses. 105

JAMES FRANK PERETI.
